(57) **CLAIM**

The ornamental design for a microbial barrier tubing clamp device, as shown and described.

DESCRIPTION

FIG. 1 is a perspective view of a microbial barrier tubing clamp showing our new design in the closed position;

FIG. 2 is a top view thereof;

FIG. 3 is another perspective view thereof in the open position;

FIG. 4 is another perspective view thereof in the open position;

FIG. 5 is a left side view thereof;

FIG. 6 is a right side view thereof;

FIG. 7 is a top view thereof;

FIG. 8 is a bottom view thereof;

FIG. 9 is a front view thereof; and,

FIG. 10 is a back view thereof.

1 Claim, 7 Drawing Sheets
